UNITED STATES PATENT OFFICE.

GEORGE A. ENSIGN, OF DEFIANCE, OHIO, ASSIGNOR TO THE DEFIANCE MACHINE WORKS, OF DEFIANCE, OHIO.

WORK-CARRIER.

SPECIFICATION forming part of Letters Patent No. 770,051, dated September 13, 1904.

Application filed January 15, 1904. Serial No. 189,146. (No model.)

To all whom it may concern:

Be it known that I, GEORGE A. ENSIGN, a citizen of the United States, and a resident of Defiance, in the county of Defiance and State of Ohio, have invented a new and Improved 5 Work-Carrier, of which the following is a full, clear, and exact description.

The invention relates to wood-working machines, such as mortising-machines, boring- 10 machines, and the like; and its object is to provide a new and improved work-carrier arranged to have a limited sliding motion between adjustable stops or a free unlimited sliding motion for any desired distance independent of the stops. 15

The invention consists of novel features and parts and combinations of the same, as will be more fully described hereinafter and then pointed out in the claims.

20 A practical embodiment of the invention is represented in the accompanying drawings, forming a part of this specification, in which similar characters of reference indicate corresponding parts in all the views.

25 Figure 1 is a side elevation of the improvement as applied to the main frame of a wood-working-machine. Fig. 2 is a transverse section of the same on the line 2 2 of Fig. 1. Fig. 3 is a front elevation of the same, and Fig. 4 30 is a longitudinal sectional elevation of the same on the line 4 4 of Fig. 3.

In mortising, boring, or otherwise working wooden articles on mortising-machines, boring-machines, and the like the bed carrying 35 the work is arranged to have a limited sliding motion sidewise as well as transversely, and for this purpose suitable stops are provided, so that the articles treated are uniform as to the size and shape of the mortises, bores, &c.

40 It is, however, frequently desirable that the bed and its work is given unlimited movement in either direction for the time being without, however, disarranging the stops, and in order to allow such movement the following arrangement is made.

The bed A for carrying the work to be operated on by the usual tools of the machine on which the device is used is mounted to slide sidewise on guideways secured to or forming

part of a slide B, mounted to slide longitudinally on guideways held on a support or bracket C, secured to or forming an integral part of the front of the main frame D of the machine. 50

On one side of the bed A (see Fig. 1) is formed a longitudinally-extending bearing E, in which is mounted to turn a shaft F, carrying at its forward end a handle F', adapted to be taken hold of by the operator for turning the shaft, and on the rear end of the said shaft 60 F is secured an abutment G, adapted to move in engagement at its front and rear faces with stops H and H' in the form of screw-rods, screwing in stop-blocks H² and H³, mounted to slide transversely on a transverse guideway 65 I, attached to and forming part of one side of the support C.

The stop-blocks H² and H³ are adapted to be moved toward and from each other on the guideway I to bring the stops H and H' the desired distance apart, and when the stop-blocks have been adjusted then they are clamped in place by clamping-screws K and K'. The screw-rods forming the stops H and H' can be screwed in or out in the stop-blocks H² 75 and H³ to obtain a minute adjustment of the stops, and then the screw-rods are clamped in position in the stop-blocks by clamping-screws J and J', as plainly indicated in the drawings. 80

For the purpose described the nuts in which screw the screw-rod stops H H' are split in the direction of the length of the nuts, and the split members of the nuts are engaged by the clamping-screws J J'. Now in loosening the clamping-screws J or J' the split members of the nut spring apart by their own resiliency to allow screwing of the screw-rod stop H or H' in either direction—that is, toward or from the abutment G—and after 90 the screw-rod stop H or H' is adjusted to the desired position then the clamping-screw J or J' is screwed up to draw the members of the split nut together to clamp the screw-rod stop H or H' securely in place. By the arrangement described the stop-blocks H² and H³ are first adjusted by the operator on the guideway I and secured in place by the clamp-

ing-screws K and K', and then the screw-rod stops H and H' are adjusted in the said stop-blocks, as above described, to obtain minute adjustment, and hence bring the stops in proper relation to the front and rear faces of the abutment G to limit the transverse sliding movement of the slide B, bed A, and the work carried thereon.

When it is desired to give an unlimited sliding movement to the slide B, the bed A, and the work thereon, then the operator swings the handle F' upwardly to turn the shaft F and to swing the abutment G out of the path of the stops H and H' to allow the slide B to travel independent of the stops to any desired position, and with it the bed A and the work thereon, without disturbing the position of the stops H and H'. A similar arrangement of stops and abutments is had between the bed A and the slide B, so as to limit the sidewise sliding movement of the bed A and the work thereon relative to the slide B or to allow of sliding the bed A and the work carried thereon any desired distance on the slide B independent of the stops and abutments. The construction of the stops and abutments is slightly varied relative to the abutment G and stops H and H' above described; but the same result is obtained.

The front face of the body A is formed with a transversely-extending guideway A', on which are adjustably held the blocks L and L', adapted to be moved toward and from each other and adapted to be secured in place by clamping-bolts L² and L³, engaging the guideway A' and the blocks L and L'. On the blocks L and L' are mounted to swing up and down the arms N and N', carrying stops O and O' in the form of screw-rods screwing in the said arms for obtaining a minute adjustment of the stops O and O' after the blocks L and L' are secured in position on the slide B. After the said screw-rod stops O and O' are adjusted they are clamped in place in the arms N and N' by clamping-screws P and P', the same as the screw-rod stops H and H', and are locked in the blocks H² and H³ by the clamping-screws J and J'.

The stops O and O' are adapted to abut against the faces of abutments Q and Q', secured to or forming integral parts of the slide B. When the arms N and N' are in a vertical position, as illustrated in Figs. 3 and 4, then the stops O and O' are in alinement with the abutments Q and Q', and consequently the sidewise movement of the bed A and the work thereon is limited; but when it is desired to give an unlimited sidewise movement to the bed A then the operator swings the arms N and N' upward to move the stops O and O' out of alinement with the abutments Q and Q', and consequently the bed A can be shifted sidewise, independent of the stops and abutments.

The device is very simple and durable in

construction and can be readily applied to various machines, it being understood that the means employed for moving the bed A sidewise on the slide B and for moving the latter transversely on the support C may be of any approved construction.

By constructing the two sets of stops in the manner described the operator standing in front of the machine can readily operate either set without leaving his position—that is, he can readily swing the arms N N' upward to move the stops O and O' out of alinement with the abutments Q and Q' or he can turn the handle F' to swing the abutment G out of the path of the stops H and H'. By making the stops H H' and O O' in the form of screw-rods it is evident that after the blocks H² H³ and L L' are adjusted and fastened in place the operator on loosening the clamping-screws J J' and P P' can screw the stops H H' and O O' toward or from the corresponding abutments to obtain an accurate setting of the stops. When this has been done, the clamping-screws J J' P P' are screwed up to securely lock the stops in place.

Having thus described my invention, I claim as new and desire to secure by Letters Patent—

1. The combination with a fixed bracket, of a slide mounted to slide on the said bracket, a bed mounted to move on the said slide, in a direction at right angles to the movement of the slide, a set of stops held adjustably on the side of the said bracket, an abutment extending between the said stops, a shaft carrying the said abutment journaled on the slide and extending in the direction of the movement of the slide, and a handle on one end of the said shaft.

2. The combination with a fixed bracket, of a slide mounted to move on the said bracket, a bed mounted to move on the said slide, in a direction at right angles to the movement of the slide, a set of stops held adjustably on the side of the said bracket, each stop consisting of a screw-rod, a block in which screws the screw-rod, a guideway fixed on the bracket and on which the block is adjustably held and means for securing the block in position on the guideway, an abutment extending between the said stops, a shaft carrying the said abutment journaled on the slide and extending in the direction of the movement of the slide, and a handle on one end of the said shaft.

3. The combination with a fixed bracket, of a slide mounted to move on the said bracket, a bed mounted to move on the said slide, in a direction at right angles to the movement of the slide, a set of stops held adjustably on the side of the said bracket, each stop consisting of a screw-rod, a block in which screws the screw-rod, a clamping-screw for locking the screw-rod in the block, a guideway fixed on the bracket and on which the block is held adjustably and means for securing the block

in place on the guideway, an abutment extending between the said stops, a shaft carrying the said abutment journaled on the slide and extending in the direction of the movement of the slide, and a handle on one end of the said shaft.

5 In testimony whereof I have signed my name

to this specification in the presence of two subscribing witnesses.
